UNITED STATES PATENT OFFICE.

WILLIAM H. MUZZY, OF DAYTON, OHIO, ASSIGNOR, BY MESNE ASSIGNMENTS, TO THE NATIONAL CASH REGISTER COMPANY, OF DAYTON, OHIO, A CORPORATION OF OHIO, (INCORPORATED IN 1906.)

CASH-REGISTER.

1,013,210.

Specification of Letters Patent.

Patented Jan. 2, 1912.

Application filed September 29, 1904. Serial No. 226,499.

To all whom it may concern:

Be it known that I, WILLIAM H. MUZZY, a citizen of the United States, residing at Dayton, in the county of Montgomery and State of Ohio, have invented certain new and useful Improvements in Cash-Registers, of which I declare the following to be a full, clear, and exact description.

This invention relates to improvements in cash registers and has more particular relation to improvements in registers provided with independent cash receptacles for different clerks.

One of the several objects of the present invention is to provide improved money receiving and handling receptacles for the different clerks, whereby their cash will be kept separate and at the same time conveniently arranged for rapidly making change.

I have shown my present improvements applied to the type of machine patented in Great Britain to Henry S. Hallwood, No. 4543 dated February 26, 1903, but it will be understood that the invention may with equal facility be applied to other types of machines.

With the above and other incidental objects in view, the invention consists in certain novel features of construction and combinations of parts, the essential elements of which are set forth in appended claims and a preferred form of embodiment of which is hereinafter specifically described with reference to the drawings which accompany and form part of this specification.

Of said drawings: Fig. 1 represents a front elevation of the type of machine above mentioned with my improvements applied thereto. Fig. 2 represents a front elevation with the cabinet removed and a number of the parts omitted. Fig. 3 represents a vertical section taken on the line 3—3 of Fig. 2, a number of the parts being omitted. Fig. 4 represents a top plan view of one of the coin receiving slides. Fig. 5 represents a detail perspective view of one of the bill receptacles or boxes, and Fig. 6 represents a detail top plan view of one of the ejector slides.

The class of machine to which my improvements are applied may be described in general terms as comprising a series of yokes 1 mounted upon a horizontal shaft 2; each of said yokes being provided with a

step frame 3 which is arranged when released to come in contact with the shanks of the amount keys 4 and thereby move the indicators to their proper positions and also allow the registering levers 5 which are mounted upon the horizontal shaft 2 to assume positions so that the amounts indicated will be registered upon the wheels 6 when the yokes 1 are returned to normal position. These yokes 1 are arranged to be operated by a main yoke 7 which is also mounted upon the horizontal shaft 2 and has a forwardly extending arm 8 terminating in a handle 9. For any detail description of said parts reference may be had to the above mentioned patent. The clerks' keys 10 also co-act with a step frame 3 and a yoke 1 in a manner similar to the amount keys in order to secure the proper clerk's indication, but this yoke carries no registering lever, consequently it has no effect upon the registering wheels 6. Laterally projecting pins 11 mounted on clerks' keys 10 engage with inclined slots 12 formed in two independent levers 13 mounted upon a transverse shaft 14. Each lever carries two arms 15 and 15^a the former of which engages a projection 16 formed upon its coin receiving slide 17 and thereby prevents the rearward movement of said slide. A yoke 18 which is pivoted upon the frame of the machine also acts as a lock against the rearward movement of the slides 17. Said yoke 18 is provided with a bar 19, which is depressed by the main yoke 7 when in its lower position thereby releasing slides 17. The arm 15^a of each lever engages a bell-crank lever 15^b. Each lever 15^a carries a pin 15^a projecting under all of the registering levers 5 of its particular counter substantially as described and shown in the patent to J. H. McCormick, No. 610,366, dated September 6, 1898.

In the type of machine shown in the present drawings the main yoke and operating handle are released by the depression of one of the clerks' keys. To accomplish this result either of said clerks' keys when depressed operates a pivoted lever 10^a which releases a detent 10^b for the clerks' keys and allows the same to drop. This detent is provided with an arm 11^a, which, when the detent drops contacts with a pin 11^b on a pivoted lever 11^c and rocks said lever upon its pivot. The upper end of this lever engages

a pin 12^a mounted upon a latch 12^b which engages a pin 8^a on the operating lever 8. By this means when either one of the clerks' keys is operated the lever 8 is released.

- 5 It will be seen from the above description that when either of the clerks' keys is depressed the latching arm 15 of its respective slide 17 is elevated and the slide thus partially unlocked. When the main yoke 10 descends and depresses the frame 18 the slide becomes wholly unlocked so that it may be operated. The coin or coins tendered in payment of a purchase are now placed in their proper recesses 20 upon the slide 17. 15 The amount of change to be returned to the customer is then procured by pressing the proper change keys 21. The upwardly extending ends 22 of said keys contact with rollers 23 mounted upon pendent arms 24 of 20 coin ejector slides 25. There is one of these slides 25 for each tube and connected to each one of these slides by a slot and pin connection is an arm 26 which is pivoted upon a transverse shaft 27. The upper end 25 of said arm contacts with a rod 28 which connects two vertical arms 29 also mounted upon the shaft 27. The upper ends of said arms 29 have slots 30 formed therein which receive pins 31 formed on pendent lugs 32 30 of the slides 17.

It will be seen from this description that the operation of any one of the change keys 21 will cause its particular slide 17 to be moved rearwardly, thereby depositing any 35 coins that may have been upon it into their respective coin tubes 33. When the proper amount of the purchase is tendered, the coin or coins are placed upon the receiving slide 17 and the clerk operates his push key 34. 40 The rearward end of this key contacts with a projection 35 formed upon one of the arms 29 and thereby forces said arm about its pivot 27, the movement of which carries slide 17 rearward and the coins placed upon 45 said slide are thus deposited in the coin tubes the same as if one of the change keys had been depressed. Each slide 17 is returned to normal position by means of a spring 36, one end of which surrounds rod 50 28, the other end is fast to a hook formed upon the rear side of one of the tubes 33. When one of the change keys 21 or the push key 34 is operated the rod 28 which is carried rearwardly engages with a wiper pawl 55 37 formed on the bell clapper 38 and rocks same about its pivot point until the said rod 28 passes clear of the pawl 37. The clapper then descends and rings the bell 39. On the return movement of the rod 28 it rocks the 60 pawl 37 about its pivot until it is clear of it, the pawl then returning to normal position.

It is, of course, to be understood that each series of change keys assigned to each clerk is provided with a similar alarm mechanism but of different tones so that each

clerk may distinguish the sound of his own bell and thereby detect an attempt to manipulate his part of the register. As shown in Fig. 2 each clerk is also provided with a series of adding wheels upon which the amounts sold by each clerk are registered, thereby enabling the proprietor to tell at a glance the amount of business done by each clerk, and if this amount added to the amount the proprietor places in each clerk's coin tubes at the beginning of the day's business does not correspond to the total amount as shown in said tubes the proprietor will not only know that a mistake has occurred but also the clerk who made the mistake and what the mistake amounts to.

As shown in Fig. 1 there is an inclined run-way 40 for each series of tubes and each run-way terminates in a cup 41 so that the amount of money ejected by the change keys 21 will roll down the incline 40 into the cups 41 from which the clerk may readily remove the same. Cylindrical boxes 42 as shown in Fig. 5 are provided to hold the bills which may be received. These boxes 45 are placed upon the slide 17 and are deposited in their respective tubes similarly to the coins.

In the mechanism above described means is provided for handling coins of all the 95 different denominations as well as one dollar bills, but it will be readily understood that the coin tubes may be extended to provide a capacity including two, five, ten and twenty dollar bills if desired without departing from the spirit of this invention.

By providing coin tubes as above described the cash may be more readily handled as it is easier to depress the proper keys for securing change than it is to select 105 coins out of the different compartments in a cash drawer.

While the form of mechanism here shown and described is admirably adapted to fulfil the objects primarily stated, it is to be 110 understood that it is not desired to confine the invention to the one form of embodiment here disclosed, for it is susceptible of embodiment in various forms all coming within the scope of the claims which follow.

Having thus described the invention what is claimed as new and desired to be secured by Letters Patent is:—

1. In a machine of the class described, the combination with clerks' selective devices, of 120 independent series of coin handling devices for the respective clerks, means for controlling the different series by the clerks' selective devices, a main operating mechanism, and means, controlled by said main operating mechanism, normally locking said coin handling devices.

2. In a machine of the class described, the combination with clerks' selective devices, of 125 independent series of coin handling devices 130

having coin ejectors, means for controlling the ejectors from the clerks' selective devices, a main operating mechanism, and means, controlled by said main operating mechanism for normally locking said ejector.

3. In a machine of the class described, the combination with a series of independent accounting devices, of independent series of 10 coin handling devices having ejectors, a common controlling means for the accounting devices and the respective coin handling devices, a main operating mechanism, and means, controlled by said main operating mechanism for normally locking said ejectors against operation.

4. In a machine of the class described, the combination with a plurality of counters, of independent series of coin delivering devices, a common controlling means for the corresponding counters and their respective series of coin handling devices, a main operating mechanism and means controlled by said main operating mechanism, normally locking said counters and said coin handling devices against operation.

5. In a machine of the class described, the combination with independent series of coin tubes, of ejector keys for each series of tubes, 30 means for separately normally locking the keys for each series of tubes, selective devices having connections for separately releasing the separate key locking means, a main operating mechanism, and means, controlled by said main operating mechanism for normally locking all said ejector keys.

6. In a cash register, the combination with a plurality of independent series of coin holding tubes, of ejectors, one series for 40 each series of tubes, means for normally separately locking each series of ejectors, and a plurality of clerks' keys, with connections therefrom for selectively releasing said locking means.

45 7. In a cash register, the combination with a plurality of independent series of coin tubes, of ejectors, one series for each series of tubes, separate guarding devices one for each series of tubes and normally preventing access to the tubes of the corresponding series, means for separately normally locking each series of ejectors, and a plurality of clerks' keys with connections whereby the keys release the locking means 50 for the corresponding series of ejectors and permit withdrawal of the corresponding guarding device.

8. In a machine of the class described, the combination with a plurality of clerks' selective devices, of independent series of coin tubes, guard plates for said tubes, ejector keys and connections therefrom to operate said guard plates, means for controlling the ejector keys from the clerks' selective devices, a main operating mechanism, and

means controlled by said main operating mechanism, normally locking said guard plates.

9. In a machine of the class described, the combination with a plurality of clerks' keys, 70 of independent series of coin tubes, ejectors for said tubes, guards for the tubes operated by the ejectors, independent means for actuating the guards, means for controlling the ejectors by the clerks' keys, a main operating mechanism, and means, controlled by said main operating mechanism, normally locking all said guards against operation.

10. In a machine of the class described, the combination with a plurality of clerks' selective devices, of independent series of coin handling devices for the various clerks, means for controlling the different series by the clerks' selective devices, independent means for withdrawing the contents of the 85 respective series of tubes, a main operating mechanism, and means controlled by said main operating mechanism, normally locking all said coin handling devices.

11. In a machine of the class described, the combination with a plurality of clerks' selective devices, of independent series of coin tubes having movable guards, locks for the guards, means for controlling the locks by the clerks' selective devices, a main operating mechanism, and means, controlled by said main operating mechanism, normally locking all said guards.

12. In a machine of the class described, the combination with a plurality of clerks' selective devices, of independent series of coin tubes for the respective clerks, guards for said tubes, ejectors for said tubes, means for operating the guards from the ejectors but permitting independent movement of 105 the guards, means for controlling the guards from the clerks' selective devices, a main operating mechanism, and means, controlled by said main operating mechanism, normally locking all said guards.

13. In a machine of the class described, the combination with a plurality of clerks' selective devices, of indicators for said devices, independent series of coin handling devices for the respective clerks, means for controlling the different series by the clerks' selective devices, a main operating mechanism, and means, controlled by said main operating mechanism, normally locking all 115 said coin handling devices.

14. In a machine of the class described, the combination with a plurality of clerks' selective devices, of a plurality of indicators, independent counters, independent series of coin handling devices for the respective clerks, means for controlling the indicators, counters, and coin handling devices according to the selective devices operated, a main operating mechanism, and means, controlled by said main operating mecha- 125 130

nism, normally locking said coin handling devices against operation.

15. In a machine of the class described, the combination with an operating mechanism, of independent groups of coin handling devices, selective means having connections for predetermining which group shall be utilized, and means released by the operation of said operating mechanism for normally locking said coin handling devices.

16. In a machine of the class described, the combination with an operating mechanism, of independent groups of coin handling devices, locking devices for each group of coin handling devices, manipulative means for selectively releasing one locking device for a desired group, and means actuated by the operation of the operating mechanism for releasing another locking device for the desired group.

17. In a machine of the class described, the combination with a plurality of groups of coin receptacles, of means for controlling the ejection of coins from said receptacles, mechanism normally rendering said means ineffective, and selective devices for rendering operative the coin ejecting controlling means of any desired group of coin receptacles.

18. In a machine of the class described, the combination with an operating mechanism, of a plurality of coin holding receptacles, of devices for controlling the deposit of coins in said receptacles, keys for ejecting coins from said receptacles and operating said controlling devices, an additional key for operating said deposit controlling devices when no change is desired, and a lock common to all of the keys controlled by the operating mechanism.

19. In a machine of the class described, the combination with registering mechanism and means for controlling said mechanism, of a series of holding devices, manipulative devices for withdrawing desired amounts of change therefrom, and means controlled by the registering mechanism controlling means for preventing operation of said manipulative devices until the operation of said controlling means.

20. In a machine of the class described, the combination with a registering mechanism and a hand operable device controlling the operation of the registering mechanism, of a series of holding devices, manually operable elements for withdrawing desired amounts of change from said holding devices, mechanism normally preventing actuation of said manually operable elements, and devices controlled by said hand operable device for disabling said preventing mechanism.

21. In a machine of the class described, the combination with duplicate groups of holding devices, of duplicate groups of

ejecting devices therefor, means for separately locking each group of ejecting devices, keys controlling said locking means, and indicating mechanism showing which key is operated.

22. In a machine of the class described, the combination with a plurality of accounting devices, of a plurality of groups of money holding devices, one group for each accounting device, manually operable elements for withdrawing desired amounts of change from said money holding devices, means normally preventing actuation of each group of said manually operable elements, and mechanism for disabling the preventing means for any group of money holding devices when the corresponding accounting device is operated.

23. In a machine of the class described, the combination with a registering mechanism, and manipulative devices determining the operation of same, of coin holding devices duplicated for each class of transaction to be entered, means normally preventing access to all said coin holding devices, but operable to give access to the coin holding devices for any desired class of transaction, and means for withdrawing coins from the coin holding devices of any desired class.

24. In a machine of the class described, the combination with accounting mechanism, of manipulative devices controlling same, coin holding devices duplicated for each class of transaction which is to be entered on the accounting mechanism, means selectively controlled by said manipulative devices for normally rendering all the coin holding devices inaccessible, but adapted to allow access to the coin holding devices for a desired class of transactions, when said manipulative devices are operated, and means for withdrawing coins from the coin holding devices so rendered accessible.

25. In a machine of the class described, the combination with an accounting mechanism, of means controlling same, means serving to control characteristics of transactions entered therein, coin holding devices duplicated for each class of transaction, means normally preventing access to all the coin holding devices, means actuated according to which transaction entry controlling means is operated for rendering accessible the coin holding devices for the corresponding class of transaction, and means for withdrawing coins from the holding devices rendered accessible.

26. In a machine of the class described, the combination with an accounting mechanism, of a plurality of groups of change holding devices, and ejectors for said change devices, means normally preventing operation of each group of ejectors, and a plurality of selective devices having connec-

- tions for separately disabling the preventing means for the corresponding group of ejectors, with means whereby all of the selective devices control operation of the accounting mechanism.
27. In a machine of the character described, the combination with an accounting mechanism, of sets of change holding devices including ejectors, means requiring an operation of the mechanism for allowing access to said change devices, and means preventing access to more than one set of devices without an intervening operation of the accounting mechanism.
28. In a machine of the character described, the combination with an accounting mechanism, of sets of change holding devices, means normally preventing access to any said set, means requiring an operation of the said mechanism for allowing access to any set of change devices and so arranged that access to another set may be had only upon another operation of the mechanism.
29. In a machine of the class described, the combination with an accounting mechanism, of a plurality of groups of change holding devices, devices for ejecting change from said holding devices, means normally preventing operation of said ejecting devices, and governing mechanism comprising hand operable devices each controlling the accounting mechanism with connections whereby said hand operable devices selectively disable the preventing means for the separate groups of ejectors.
30. In a machine of the class described, the combination with a registering mechanism and a main operating device therefor, of a plurality of groups of coin holding devices and groups of ejectors for withdrawing desired amounts of coin from said holding devices, devices for separately locking each of said groups of ejectors, means for additionally locking all said groups of ejectors, connections from said operating mechanism for releasing the additional lock, and manipulative means for selectively releasing the separate locking devices for said groups.
31. In a machine of the class described, the combination with a series of groups of money holding devices and groups of ejectors for withdrawing desired values in money from said holding devices, of devices separately locking each of said groups of ejectors, means for additionally locking all said groups, a hand operable mechanism having connections for disabling said additional locking means, and manually operable keys having connections for selectively disabling said separate locking devices.
32. In a machine of the character described, the combination with an operating mechanism, of independent groups of coin handling devices; means for determining which group of devices will be made accessible, and means controlled by the operating mechanism for rendering all of the coin handling devices of the selected group accessible.
33. In a machine of the character described, the combination with an operating mechanism, of independent groups of coin handling devices; selective locking means for determining which group of devices will be made accessible, and independent locking means controlled by the operating mechanism, for rendering all of the coin handling devices of the selected group accessible.
34. In a machine of the class described, the combination with a registering mechanism and operating mechanism therefor, of change delivering devices comprising a series of change holding tubes and an ejector for each tube, means for normally preventing actuation of said ejectors, and devices operated by said operating mechanism for disabling said preventing means.
35. In a machine of the class described, the combination with a registering mechanism, and an operating mechanism therefor, of change delivering devices comprising change holding tubes, and manually operable ejectors for said tubes, means normally locking said ejectors against operation, and connections actuated by said operating mechanism for releasing said locking means.
36. In a machine of the class described, the combination with a registering mechanism and an operating mechanism therefor, of change delivering devices comprising change holding tubes and manually operable ejectors for said tubes, and means requiring an operation of said operating mechanism to permit actuation of said ejectors.
37. In a machine of the class described, the combination with a registering mechanism, and an operating mechanism therefor, of a change delivering mechanism including a series of coin tubes and ejectors for withdrawing desired amounts of coin from said tubes, devices normally preventing actuation of said ejectors, and means requiring an operation of said operating mechanism for disabling said preventing means.

Intestimony whereof I affix my signature, in the presence of two witnesses.

WILLIAM H. MUZZY.
